UNITED STATES PATENT OFFICE.

REUBEN NAKIAN, OF WEST HOBOKEN, NEW JERSEY.

DESIGN FOR A TOY BROOM.

59,855.

Specification for Design.

Patented Nov. 29, 1921.

Application filed August 17, 1921. Serial No. 493,185. Term of patent 14 years.

To all whom it may concern:

Be it known that I, REUBEN NAKIAN, a citizen of the United States, and a resident of West Hoboken, in the county of Hudson and State of New Jersey, have invented a new, original, and ornamental Design for Toy Brooms, of which the following is a specification, reference being had to the accompanying drawing, forming part thereof.

The figure is a view in front elevation of a toy broom, showing my new design, the dot and dash lines indicating the position of the broom handle.

The design includes the head, body and arms of a female figure, in the lower end of which, bristles are secured, representing the skirt of the figure.

I claim:

The ornamental design for a toy broom, as shown and described.

REUBEN NAKIAN.
